(57) **CLAIM**

The ornamental design for a vehicle tail light, as shown and described.

DESCRIPTION

FIG. 1 is a front left perspective view of a vehicle tail light according to the present invention.

FIG. 2 is a front view of the tail light shown in FIG. 1.

FIG. 3 is a left side view thereof.

FIG. 4 is a top view thereof; and,

FIG. 5 is another front view of the vehicle tail light shown in FIGS. 1-4, but mounted on a vehicle and with the rest of the vehicle shown in broken lines, which form no part of the claimed design.

The invention contemplates a mirror image vehicle tail light on the opposite side of the vehicle.

In the FIGS. 1 through 4, the vehicle tail light is shown within the broken line, and the elements shown outside the broken line in de-emphasized and half-tone portions form no part of the claimed invention, but are instead included to show environmental aspects thereof. For purpose of illustration the vehicle tail light is shown in a darker tone. The darker tone itself forms no part of the claimed design.
